UNITED STATES PATENT OFFICE.

ROBERT A. RUSSELL, OF RUSTBURG, VIRGINIA.

ROAD SCRAPER.

Application filed December 9, 1926. Serial No. 153,652.

The present invention relates to road scraper or shaver for smoothing dirt, top soil, or other comparatively soft surface roads and the object of the invention is to provide a structure which operates upon the principle of shearing practically parallel to traffic rather than the bouncing method of the blade of the usual road scraper which is disposed almost perpendicularly to traffic and leaves a transversely corrugated road surface.

Another important object of the invention lies in the provision of a device of this nature which is simple in its construction, thoroughly efficient and reliable in use, strong and durable, inexpensive to manufacture and otherwise well adapted to the purpose for which it is designed.

With the above and numerous other objects in view as will appear as the description proceeds, the invention resides in certain novel features of construction, and in the combination and arrangement of parts as will be hereinafter more fully described and

claimed.

In the drawing:

Figure 1 is a top plan view of the device embodying the features of my invention,

Fig. 2 is a side elevation thereof,

Fig. 3 is a rear elevation thereof,

Fig. 4 is a longitudinal section therethrough taken substantially on the line 4—4 of Fig. 1,

Fig. 5 is a perspective view of one of the blades,

Fig. 6 is a fragmentary sectional rear elevation of another embodiment of the invention,

Fig. 7 is a perspective view of another embodiment of the blade.

Referring to the drawing in detail, and particularly to the preferred embodiment of the invention shown in Figures 1 to 5 inclusive, it will be seen that the scraper includes a plurality of longitudinally extending blades A co-extensively arranged one along side of the other in spaced relation and a pair of side blades B which extend a distance to the rear of the blades A. Each blade includes an elongated web 5 having top and bottom flanges 6 which taper towards the front and merge into a rounded front edge of the web 5. These flanges are preferably corrugated as is indicated at 8, said corrugations being disposed at the forward ends of the flanges, each corrugation

extending transversely thereof. Apertures 10 are provided in the forward ends of the blades and are pierced by a rod 11 having spacing elements 12 thereon for holding the forward ends of the blades in a predetermined spaced relation. The rear ends are slightly spaced from one another. A cross bar 14 has its ends hinged to the rear ends of the blades B as denoted at 15 so as to allow a certain side play at the rear end of the device. The rear ends of the blades A are free. An inverted U-shaped rod 16 has its extremities piercing openings in the flanges 6 at the top rear portions of the blades B so that the bight of the rod 16 extends over the rear free ends of the blades A to limit the upward swinging movement thereof as is clearly indicated in dotted lines in Fig. 2 in order to prevent portions of the free rear ends of the blades A from overlapping or becoming caught one in another. I provide plates 18 extending between adjacent edges of the flanges 6 at or adjacent their rear ends.

The blades A and B may be made each of an integral formation being cast in the formation shown or machined from I beams. However, other embodiments may be utilized to advantage such as the embodiment shown in Fig. 7 wherein an elongated web 5' may be constructed of wood or the like and has metal forwardly tapering flanges 6' on its upper and lower edges, said flanges having their forward portions corrugated as at 8'. In this embodiment of the invention the rear end of the web 5' is formed with a laterally extending head 18' terminating flush with the adjacent edges of the flanges 6' to function in the same manner as plate 18 heretofore referred to. The forward rounded edges 7 are substantially feathered edges for cutting purposes. The corrugations tend to scrape the roadway while the remaining portions of the flanges function as drags. The forward ends of the side blades B are provided with arcuate series of apertures 20 with which clevises or the like may be engaged for the purpose of towing the device in connection with a wagon, truck, tractor, or any other suitable draft means. The width, length, weight, and materials and the frame style do not form the essence of this invention and may be varied to suit the circumstances of the user. The blades are reversible as will be apparent so that when the lower flanges wear the blades may be individually reversed

or the entire device may be reversed which would merely necessitate the shifting of the bar 16 to the other side as will be quite apparent. The depth at which the device will tend to dig is governed by the apertures 20 into which the clevises or the like are put as will also be apparent.

In Figure 6 I have shown an embodiment of the invention which may be used to advantage wherein I eliminate the plates 18 or equivalent means and use instead pins 21 projecting upwardly from the rear ends of the blades A and piercing openings 22 in rod 16' which is similar to rod 16 hereinbefore referred to. These pins 21 will tend to maintain the rear ends of the blades A at an approximate equal spaced relation.

By dragging this device along the road with a sufficient number of blades all running parallel to traffic, the road may be smoothed, sheared, and tracked and no cross ridges will be formed. The frame structure may be made for a drag of wagon type or motor propelled machine, but of course, I do not desire myself to be limited to any particular draft means.

It is thought that the construction, utility, and advantages of this invention will now be apparent to those skilled in this art without a more detailed description thereof. The present embodiments of the invention have been disclosed in detail merely by way of examples, since in actual practice they attain the features of advantage enumerated as desirable in the statement of the invention and the above description. It will be apparent that changes in the details of construction, in the sizes, in the materials, and in the combination and arrangement of parts will be resorted to without departing from the spirit or scope of the invention as hereinafter claimed or sacrificing any of its advantages.

Having thus described my invention what I claim as new is:—

1. A device of the class described including a plurality of blades disposed in co-extensive relationship, means for holding said blades in said relationship, each blade including an elongated web having a flange on one edge thereof, said flange tapering forwardly.

2. A device of the class described including a plurality of blades disposed in co-extensive relationship, means for holding said blades in said relationship, each blade including an elongated web having top and bottom flanges tapering forwardly.

3. A device of the class described including a plurality of blades disposed in co-extensive relationship, means for holding said blades in said relationship, each blade including an elongated web having a flange on one edge thereof, said flange tapering forwardly, the forward portion of said

flange having a plurality of transverse corrugations.

4. A device of the class described including a plurality of blades disposed in co-extensive relationship, means for holding said blades in said relationship, each blade including an elongated web having top and bottom flanges tapering forwardly, said flanges having their forward portions provided with a plurality of transverse corrugations.

5. A device of the class described including a plurality of blades disposed in co-extensive relationship, means for holding said blades in said relationship, each blade including an elongated web having a flange on one edge thereof, said flange tapering forwardly, said blades being disposed in spaced relation, and means at the rear ends of said blades for preventing portions thereof from overlapping.

6. A device of the class described including a plurality of blades disposed in co-extensive relationship, means for holding said blades in said relationship, each blade including an elongated web having a flange on one edge thereof, said flange tapering forwardly, the rear ends of said blades being free and means associated with said free rear ends to prevent portions thereof from overlapping.

7. A device of the class described including a plurality of co-extensive spaced parallel blades, a rod piercing openings in the forward portions of the blades, spacing means on said rod, the rear ends of said blades being free, and means on the rear ends of said blades for preventing portions thereof from becoming overlapped.

8. A device of the class described including a plurality of co-extensive spaced parallel blades, a rod piercing openings in the forward portions of the blades, spacing means on said rod, the rear ends of said blades being free, and means on the rear ends of said blades for preventing portions thereof from becoming overlapped, each blade including a web having a flange on one edge thereof extending longitudinally therewith and to the side thereof, said flange tapering forwardly.

9. A device of the class described including a plurality of co-extensive spaced parallel blades, a rod piercing openings in the forward portions of the blades, spacing means on said rod, the rear ends of said blades being free, and means on the rear ends of said blades for preventing portions thereof from becoming overlapped, each blade including a web having a flange on one edge thereof extending longitudinally therewith and to the side thereof, said flange tapering forwardly, the forward portion of said flange having a plurality of transverse corrugations.

10. A device of the class described including a pair of spaced parallel co-extensive blades, a plurality of spaced parallel co-extensive blades between the pair of blades, 5 said plurality of blades terminating short of the rear ends of the pair of blades, means pivoting the forward portions of the blades together in spaced relation, the rear ends of the plurality of blades being free, means 10 for limiting the upward movement of the free rear ends of the plurality of blades.
11. A device of the class described including a pair of spaced parallel co-extensive blades, a plurality of spaced parallel co- 15 extensive blades between the pair of blades, said plurality of blades terminating short of the rear ends of the pair of blades, means pivoting the forward portions of the blades together in spaced relation, the rear ends 20 of the plurality of blades being free, means for limiting the upward movement of the free rear ends of the plurality of blades, means on the blades for preventing the rear portions thereof from becoming overlapped.
- 25 12. A device of the class described including a pair of spaced parallel co-extensive blades, a plurality of spaced parallel co-extensive blades between the pair of blades, said plurality of blades terminating short 30 of the rear ends of the pair of blades, means pivoting the forward portions of the blades together in spaced relation, the rear ends of the plurality of blades being free, means for limiting the upward movement of 35 the free rear ends of the plurality of blades, means on the blades for preventing the rear portions thereof from becoming overlapped, a cross bar hingedly engaged with the rear ends of the pair of blades.
13. A device of the class described including a pair of spaced parallel co-extensive blades, a plurality of spaced parallel co-extensive blades between the pair of blades, 40 said plurality of blades terminating short of the rear ends of the pair of blades, means pivoting the forward portions of the blades together in spaced relation, the rear ends of the plurality of blades being free, means 45 for limiting the upward movement of the free rear ends of the plurality of blades, 50 means on the blades for preventing the rear portions thereof from becoming overlapped, a cross bar hingedly engaged with the rear ends of the pair of blades, each blade comprising a web having a flange extending 55 longitudinally on one edge and tapering forwardly.
14. A device of the class described including a pair of spaced parallel co-extensive blades, a plurality of spaced parallel co-extensive blades between the pair of blades, 60 said plurality of blades terminating short of the rear ends of the pair of blades, means pivoting the forward portions of the blades together in spaced relation, the rear ends of 65 the plurality of blades being free, means for limiting the upward movement of the free rear ends of the plurality of blades, means on the blades for preventing the rear portions 70 thereof from becoming overlapped, a cross bar hingedly engaged with the rear ends of the pair of blades, each blade comprising a web having a flange extending longitudinally on one edge and tapering forwardly, the forward portion of the flange having trans- 75 verse corrugations.

In testimony whereof I affix my signature.
ROBERT A. RUSSELL.
